UNITED STATES PATENT OFFICE.

CHARLES G. JUNEAU, DECEASED, LATE OF WAUWATOSA, WISCONSIN, BY ANNA K. JUNEAU, ADMINISTRATRIX, OF WAUWATOSA, WISCONSIN, AND WALTER C. MARSHALL, OF MILWAUKEE, WISCONSIN.

REFRIGERATOR.

Application filed May 25, 1928. Serial No. 280,536.

Our invention relates to refrigerators wherein an improved method of air circulation is obtained and more adequate refrigeration or cooling of the articles or food products provided.

Our improved refrigerator, also adapted for domestic or commercial use, is especially designed for use in the buffet end of railroad dining cars where considerable difficulty is encountered in providing proper refrigeration because of the location of the refrigerators and the utilization of limited space at the buffet end of the dining cars.

Our invention is embodied in a refrigerator especially adapted for containing fruits, and the like, in connection with which proper chilling temperatures are necessary to maintain the fruit or similar food products at a proper temperature and in suitable condition, without, however, permitting contamination of any of the food products by reason of the presence of other articles in the refrigerator.

The invention contemplates a construction whereby a more uniform cold temperature of the various food holding compartments of the refrigerator may be obtained and the desired chilling of the various food stuffs accomplished.

The objects and advantages of our invention will be readily comprehended from the detailed description of the drawings, wherein:

Figure 1 is a sectional elevation of one form of our improved refrigerator.

Figure 2 is an enlarged detail sectional view of one of the food holding compartments.

Figure 3 is a sectional elevation of the upper portion of the refrigerator shown in Figure 1; the view being taken substantially at right angles to the disclosure in Figure 1.

Figure 4 is a sectional view, similar to Figure 2, of a food holding compartment, illustrating a modification.

Figure 5 is a sectional elevation of the upper portion and one of the food holding compartments of the refrigerator illustrating a modified form.

Figure 6 is a sectional view of the food

holding compartment shown in Figure 5; the view being taken substantially at right angles to Figure 5.

Figure 7 is a detail sectional view of a portion of food holding compartment, illustrating the means employed in Figure 5 for operating the air controlling means of the food holding compartments.

In the exemplification as disclosed in the first three figures of the drawings, our invention is shown applied to a type of refrigerator especially adapted for use in railroad dining cars wherein mechanical refrigeration is generally employed; although it will be understood that our invention is equally adapted for use in connection with refrigerators for commercial and domestic use and wherein ice may be employed as the cooling medium.

The refrigerator as illustrated in Figure 1 consists of the outer double walls 15 of any suitable material, preferably of wood of proper thickness, having cork-board insulation 16 therebetween and arranged throughout the entire wall; the cork-board insulation being preferably sealed with a non-odorous cold seal cement. The refrigerator, as illustrated in Figure 1, is of what may be termed the single type, namely with a single tier of food holding compartments and refrigerating compartment, with the forward side provided with a suitable door or plurality of doors as indicated at 17 and 18 in Figure 3; the door 17 providing access to the refrigerant-holding compartment 19, while the door 18 permits access to and constitutes one side wall of the food-holding compartments. It is obvious that the door 18 may extend throughout the entire food holding portion of the refrigerator or may consist of door sections in number equaling the number of food holding compartments so that access to a single compartment may be had.

The upper part of the refrigerator is shown provided with a mechanical refrigerating unit generally indicated at 20, which may be of a well known type involving what are known as fin coils 21. This refrigerating unit is arranged in a compartment formed by the insulated wall or baffle 22,

consisting of cork-board covered with sheet metal. A portion of the baffle 22 extends vertically in parallel spaced relation with one side wall of the refrigerator, while the bottom portion is arranged at an inclination and terminates in spaced relation with the opposite side wall of the refrigerator. The lower end of the bottom portion is preferably provided with an upstanding lip or flange at 23 for the purpose of preventing dripping of the condensate into the lower part of the refrigerator. It will be understood that the partition or baffle 22 extends from front to rear so as to provide a complete enclosure or compartment for the refrigerating medium, except for the air passages 24 and 25 which extend from top to bottom of the refrigerator; passage 24 communicating with the refrigerant holding compartment 19 at the end of the sloping bottom portion of the baffle 22, namely at point 26, while the air passage 25 communicates with the upper part of the refrigerant holding compartment 19, at the point 27 above the baffle 22.

As the mechanical refrigerating unit is of a well known construction and forms no part of our invention, a specific description of its construction and operation need not be entered into; it being understood that ice or any other cooling medium may be employed.

The refrigerator, as shown in Figure 1, comprises a plurality of independent food holding compartments formed by the walls 28, 28; preferably of metal, or other suitable conducting material,—extending from the rear wall of the refrigerator to the front wall as shown in Figure 3, so as to provide independent compartments, merely having communication with the air circulating portion of the refrigerator at the upper ends of the compartments as later described. The walls 28 are shown with inwardly flanged bottom portions for supporting the bottoms 29 of the respective compartments; the bottoms being either permanently or slidably mounted in place. The walls 28 are arranged in spaced relation with the side walls of the refrigerator in order to provide the air passages 24 and 25; and these food holding compartments are also arranged to provide an air passage 30 at the bottom of the refrigerator whereby communication between the air passage 24 and the air passage 25 is provided to enable full and ample circulation of the air beneath the lowermost compartment and likewise along the opposite side walls of said compartments.

As will be seen in Figure 1, a plurality of separate non-communicating food-stuff holding compartments are provided adapted to separately hold various food articles and each constituting a separate chilling chamber through which proper circulation is obtained by means of the pivotally mounted

lips or shutters 31 arranged at the upper ends of both side walls 28 of each compartment. These shutters, like the side walls 28, are preferably of sheet metal,—or other suitable temperature conducting material,—with the lower longitudinal edges of the shutters hingedly secured at 32 to the upper ends of the walls 28, to permit the shutters to move outwardly into the air passages 24 and 25 when in open position or to assume a position substantially parallel and in alignment with the side walls 28 when the temperature of the respective compartments reaches the desired low degree.

In the exemplification of the invention disclosed in Figures 1 to 3, the shutters or lips 31 are automatically controlled by means of a pressure providing element or liquid enclosed in the hermetically sealed container 33 shown in the nature of a copper bellows to permit ready expansion and contraction of the bellows through the action of the liquid therein; the liquid being of a well known character whose boiling point is approximately 32 degrees Fahrenheit, so that expansion of the bellows will take place as soon as the temperature in the refrigerator rises to a predetermined degree. The bellows is shown provided with an upstanding rod 34 slidably mounted in a bracket 35 secured to one wall of the refrigerator (constituting one side wall of the foot holding compartment); the rod being preferably secured to the bellows and having its lower end threaded at 36 to receive a nut 37 for controlling the tension of a spring 38 encircling the rod 34 intermediate of the nut 37 and the guide bracket 35. It is evident that upon screwing nut 37 upwardly on rod 34 the tension of spring 38 is increased and therefore the effective moment of operation of the bellows controlled or retarded; while screwing nut 37 downwardly on the rod 34 enhances the moment of operation, or in other words causes operation of the mechanism at a lower temperature. The upper end of rod or plunger 34 has a pair of rods 39, 39 pivotally secured thereto at 40; the outer ends of rods 39 being pivotally secured at 41, 41 to the two opposite shutters or lips 31, 31 so that simultaneous operation of both lips or shutters is induced when bellows 33 expands or when the latter contracts and spring 38 expands.

Each of the food-stuff holding compartments 42 are shown provided with a thermometer at 43 mounted in a proper protective holder or shield 44 so that the mercury or fluid holding glass-tube may not be broken.

In the exemplification, passage or duct 24—which extends from front to rear of the refrigerator the full width of the food-stuff holding compartments, constitutes the

cold air duct leading from the throat or orifice 26, at the lowest point in the refrigerant compartment 19, to the bottom of the refrigerator where it connects with bottom 5 passage 30, which in turn connects with the bottom of what constitutes the warm or rising air passage or duct 25, thereby causing circulation of cold air along the sides of the food-stuff compartments, which are independent 10 of each other and may therefore be arranged to different degrees of temperature if desired, by the shutter controlling means, so as to adapt the various compartments to different commodities requiring 15 varying degrees of temperature.

As the walls 28 of the food-stuff holding compartments extend from front to rear, the only points of communication between the compartments and the remainder 20 of the refrigerator are through the openings at the tops of the side walls controlled by the pivoted lips or shutters 31. The chilled air from the refrigerant compartment 19 in the upper end of the refrigerator 25 flows down through throat or opening 26 into passage or cold air duct 24 and down to the bottom of the refrigerator. With the lips or shutters 31 extending upwardly outward into passage 24, it is apparent, that 30 cold air will flow through the opening at the top of each food holding compartment and drop or flow toward the shelf or bottom 29 of the respective compartments and therefore caused to pass over and around 35 all of the food-stuff in each compartment. This movement of the cold air is caused to take place because the lip or shutter 31 in the opposite side of the food-stuff compartment is in similar open position and 40 affords communication between the opposite side of the compartments 42 and the warm or rising air passage or duct 25. As a result, a complete displacement of warm air takes place in each compartment and hence 45 a complete chilling of all of the food-stuffs is accomplished.

The warm air in duct or passage 25 will rise toward the top of the refrigerator and made to pass along baffle 22 and pass 50 through passage 27 into the top of the refrigerant compartment 19, coming into contact with the refrigerant medium and when properly chilled made to flow downwardly into cold air passage 24.

A continuous circulation of cold air is therefore constantly maintained.

With the lips or shutters of each compartment 42 separately controlled, it is obvious 55 that a degree of temperature in each compartment, in keeping with the foodstuff contained in the compartment, may be obtained by regulating the spring pressure of the plungers or rods 34 so that the moment of effective pressure in the liquid holding con-

tainers or bellows 33 may be retarded or advanced as the case may be.

As the temperatures in the compartments 42 rise beyond the desired degree, the liquid in the containers or bellows 33 boils and expands, causing the plunger or rod 34 to move upwardly, thereby forcing the lips or shutters 31 outwardly; increasing the size of the openings in the upper parts of the compartments 42, allowing a greater amount 70 of cold air to enter from passage 24 and an outflow of warm air into passage 25. On the other hand, as the temperature in each compartment 42 drops below a preselected degree, the containers or bellows 33 contract and the plungers or rods 34 move 75 downwardly through the action of the springs 38, thus causing the rods 39 to draw the lips or shutters 31 upwardly toward closed position; this condition maintaining 80 until the temperature in a compartment 42 rises above the pre-selected temperature; it being understood, of course, that the respective springs 38 have been previously 85 regulated to effect operation at the pre-selected temperatures.

In Figure 4 we illustrate a modification of the invention in so far as the lip or shutter controlling means is concerned; the refrigerator in all other respects being similar in construction to that previously described and shown in Figure 1; being provided with the cold air passage 24 and the warm air passage 25 arranged vertically at opposite sides of the food-stuff compartment 42. The food-stuff compartment is similarly formed; having the metallic or temperature conducting side walls 28 extending from front to rear transversely of the refrigerator, and each provided at top 95 with a hingedly connected lip or shutter 31, like in the construction shown in Figure 1.

The shutters or lips 31 are controlled by the rods 39, 39, pivotally connected to the plunger-rod 34, slidably mounted in the 100 guide bracket 35 and encircled by the spring 38, whose tension may be regulated by the nut 37.

The plunger 34 in this construction is 105 operatively connected to a suitable magnet coil shown at 45, with lines or wires 46 arranged to provide a suitable electrical circuit (the circuit involving any suitable 110 source of electrical energy not shown) which is affected by a suitable electrical contact making thermometer indicated at 47; the magnet and its appurtenances functioning in place of the liquid holding containers or bellows 33 shown in Figure 1. The operation of the lips or shutters in this construction is similar to that previously described; the compression spring 38 causing the lips 31 to close when the magnet is deenergized; energizing of the magnet causing the 115 120 125 130

plunger or rod 34 to rise, while spring 38 causes it to move downwardly.

In Figures 5 to 7, inclusive, we illustrate another modification of the shutter or lip controlling means; the construction of the refrigerator proper with its separate food-stuff holding compartments formed by the walls 28, having the hingedly connected lip or shutters 31, and the air passages 24 and 25 being substantially the same as in the constructions heretofore described.

The construction shown in Figures 5 to 7 involves manual control of the lips or shutters 31 through the manipulation of mechanical means consisting of a rod 48 disposed transversely of each food-stuff holding compartment 42 and rotatably mounted at an intermediate point in a suitable bracket 49 secured to the rear side wall of the refrigerator adjacent to the top of each food compartment 42. One end of the rod 48 extends through one of the main side walls of the refrigerator, with the outer end preferably provided with a suitable knob or finger-grasp 50 whereby the rod 48 may be rotated.

The rod 48 at suitable places is shown threaded at 51 where the rod extends through internally threaded blocks or sleeves 52, 52, which extend through holes 53, in the lips or shutters 31 and are pivotally connected to the shutters in any suitable manner, as for example by the brackets 54, one of which is shown in dotted lines in Figure 7. The swiveled connection between the sleeve and the bracket permits the angularity of the shutter to be altered; it being understood that movement of the pivotal connection between sleeve 52 and bracket 54 through the arc of a circle may be effected either by slight sliding movement of bracket 54 on the shutter or by means of a slot in sleeve 52 for the pivot pin carried by bracket 54.

The food compartment 42 is shown provided with a thermometer at 43 located in the upper part of the compartment. In the event the temperature in a compartment is found to be improper, say too warm, rod 48 is rotated so as to cause the sleeves or blocks 52 to ride toward the ends of the rod 48, thereby causing the lips or shutters 31 to move outwardly into the air ducts or passages 24 and 25. This will induce a greater inflow of cold air from passage 24 and more rapid outflow of warm air into passage 25 and hence cause a proper chilling of the food-stuffs in the compartments 42. On the other hand, if the temperature in any one of the compartments is too low, proper rotation of rod 48 will cause movement of the sleeves or blocks 52 toward each other and effect a closing or partial closure of the openings at the tops of the compartments by the

upward movement of the shutters or lips 31.

It is apparent that with either form of our invention greater flexibility and adaptability of the refrigerator to the many different operating environments and conditions is provided and that the proper temperatures of the various food-holding compartments may be controlled and regulated in keeping with the food contained; while at the same time each shelf or compartment bottom may be completely covered with food without hindering proper air circulation. Furthermore, with our improved refrigerator employing separate, non-communicating compartments for the food-stuffs, contamination is made impossible.

It will be understood, of course, that the bottom portion of baffle 22 is preferably made sloping toward one side of the refrigerator where it may be provided with a drip pipe for suitable draining, as is usual in refrigerators; a showing of the drain pipe being deemed unnecessary.

For purposes of illustration, the invention has been shown applied to a single type of refrigerator, but it is apparent that it may be readily incorporated in the large or double type of refrigerator where the food holding compartments are arranged on both sides of the cold air passage 24 in the manner disclosed in our pending application Serial No. 180,640.

What we claim is:

1. A refrigerator having in its top a refrigerant holding compartment formed by a baffle arranged to constitute the bottom and side walls of the compartment, the side wall being in spaced relation with the main side and top walls of the refrigerator, a plurality of separate food-stuff holding compartments arranged vertically beneath the bottom of the baffle and spaced from two of the main side walls of the refrigerator so as to provide vertically extending air passages on opposite sides of said last mentioned compartments, said passages communicating with each other beneath the lowest food-holding compartment, one passage communicating at top with the bottom of the refrigerant compartment while the other passage communicates with the top of said refrigerant compartment, the side walls of the food-stuff compartments adjacent to the tops thereof being provided with shutters hingedly connected at bottom to said side walls so as to swing outwardly into said air passages, and means connected to the shutters of each compartment whereby said shutters may simultaneously be moved into open or closed positions.

2. A refrigerator provided in its top with a refrigerant holding compartment, air passages disposed vertically of the refrigerator and communicating with each other at the bottom, each of said passages communicat-

- ing with said compartment at different elevations to constitute a cold air passage and a warm air passage, food-stuff holding compartments arranged one above the other intermediate of said air passages and having temperature conducting side walls, shutters pivotally secured to the upper ends of said side walls for establishing communication between said air passages and the respective food-stuff compartments, means operatively connected to the shutters of each compartment for simultaneously moving the same, and controllable means for actuating said first means.
3. A refrigerator provided in its top with a refrigerant holding compartment having an air outlet in its bottom and an air inlet at its top, food-stuff holding compartments arranged one above the other in spaced relation with the main side walls of the refrigerator to provide air passages extending on opposite sides of the food-stuff compartments and communicating with each other beneath the bottom compartment, one of said passages communicating with said air outlet while the other communicates with said air inlet, each of said food-stuff compartments having solid bottoms, shutters hingedly secured at bottom to the tops of the opposite side walls of said food-stuff compartments so as to permit the upper ends of the shutters to swing outwardly into said air passages, means operatively connected to the opposing shutters of each compartment for holding the same in their adjusted positions, and means for actuating said first means.
4. A refrigerator provided in its top with a refrigerant holding compartment having an air outlet in its bottom and an air inlet adjacent to its top, foodstuff holding compartments having temperature conducting side walls arranged beneath said first compartment in spaced relation with the main side walls of the refrigerator to provide vertical air passages on opposite sides and communicating with each other at the bottom of the refrigerator, one of said passages communicating with said air outlet while the other passage communicates with said air inlet, shutters hingedly secured to the opposite side walls of the food-stuff holding compartment so as to swing outwardly into said air passages, means operatively connected to the opposite shutters of each compartment for holding the same in their adjusted positions, and temperature controlled means for actuating said first means.
5. A refrigerator provided with insulated top, bottom and side walls, an insulated partition wall extending from side to side in the upper part of the refrigerator, the lower part of said partition wall extending laterally in a downwardly sloping manner, the partition wall being formed to provide a cold air passage at the free end of said laterally disposed portion and a warm air passage at the upper end of the partition, a plurality of food-stuff holding compartments arranged one above the other beneath said laterally extending portion of said partition wall so as to provide vertically disposed air passages along the sides of said compartments, said compartments having imperforate bottoms, the upper ends of opposite side walls of the compartments being hingedly secured in place to permit said portions to swing outwardly into said vertically disposed air passages, and means operatively connected with the hinged portions of the opposite side walls of each compartment whereby said portions may be controlled.
6. A refrigerator provided with insulated top, bottom and side walls, an insulated partition wall disposed from front to rear in spaced relation with a side wall to provide a warm air passage therebetween and arranged in the upper part of the refrigerator, the lower end of said partition wall being disposed laterally toward the opposite side wall and terminating in spaced relation thereto to provide a cold air passage, food-stuff holding compartments arranged beneath said laterally disposed portion of the partition wall and having vertical walls arranged in spaced relation with the side walls of the refrigerator, the opposite side walls of the food stuff holding compartments adjacent the tops having pivoted portions adapted to move outwardly into the vertically disposed air passages at opposite sides of said compartments, and means for regulating the position of the pivoted portions of said compartment walls whereby the circulation of cold air through each compartment may be separately controlled.
7. A refrigerator provided with insulated top, bottom and side walls, an insulated partition wall disposed from front to rear in spaced relation with a side wall to provide a vertically disposed warm air passage communicating at top with the opposite side of said partition wall, the lower end of said partition wall being disposed laterally toward the opposite side wall and formed to provide a downwardly disposed cold air passage at the end of said laterally disposed portion, food-stuff holding compartments arranged one above the other beneath said laterally disposed portion and having side walls arranged in spaced relation with both of said refrigerator side walls, said compartments having imperforate bottoms, the bottom of the lower compartment being spaced from the bottom of the refrigerator, said compartment walls extending from front to rear of the refrigerator, with the upper ends of both side walls of each com-

partment being hinged to swing vertically outward into the air passages, and temperature controlled means for independently regulating the two portions of the opposite 5 walls of each compartment.
